UNITED STATES PATENT OFFICE.

THOMAS T. WOODWARD, OF SOUTH READING, MASSACHUSETTS, ASSIGNOR TO HIMSELF,
AND WHITON, BROWNE AND WHEELWRIGHT, OF BOSTON, MASSACHUSETTS.

SIGNAL APPARATUS.

Specification of Letters Patent No. 28,336, dated May 15, 1860.

To all whom it may concern:

Be it known that I, THOMAS T. WOODWARD, of South Reading, in the county of Middlesex and State of Massachusetts, have 5 invented certain new and useful Improvements in Revolving Signal Apparatus, and that the following description, taken in connection with the accompanying drawings hereinafter referred to, forms a full and 10 exact specification of the same, wherein I have set forth the nature and principles of my said improvements by which my invention may be distinguished from all others of a similar class, together with such 15 parts as I claim and desire to have secured to me by Letters Patent.

The figures of the accompanying plate of drawings represent my improvements.

Figure 1 is a central vertical section of my 20 improved revolving signal apparatus. Fig. 2 is a side view with the outer casing removed. Fig. 3 is a transverse horizontal section taken in the plane of the line A B Fig. 1. Fig. 4 is a plan or top view of the 25 top plate of the inside cylinder.

I have heretofore made an improvement in 30 signal apparatus for vessels for which I have made application for separate Letters Patent which consisted of a lantern having a series of fixed lights with which was combined an arrangement of devices consisting of a tube or barrel containing blue or other pyrotechnic lights, which were ignited at any desired moment by the movement of a 35 spring hammer actuated by pulling a cord or otherwise.

The present invention consists in a new 40 arrangement of devices whereby a series of pyrotechnic lights can be successively ignited instead of only one as was the case in my former apparatus in which one pyrotechnic light became extinct before another one could be inserted and ignited.

By my present portable apparatus a continuous intense light can be produced if 45 desired or a series of rockets or other signals can be successively exploded without cessation, no time being lost in recharging the apparatus. To produce these results I 50 use a circular many-chambered apparatus in which blue lights, rockets or other pyrotechnic lights are placed at proper intervals apart and separated by partitions to prevent more than one light from being ignited

at a time by sparks &c. and made to receive 55 an intermittent rotary motion and ignite each light in succession by means of a spring-hammer striking a percussion cap the whole being actuated by simply pulling a cord. By this means one light can be 60 ignited before the preceding one has burned out or the whole series can be almost instantaneously set in operation.

a a a in the drawings represent a water-tight casing, in which the apparatus is 65 enclosed having a suitable cover *b b*.

c c is a hollow cylinder containing any 70 number of sockets *d d* &c. in which are placed a series of blue or other pyrotechnic lights or charges *e e*, &c., the top of these terminating in a cylindrical chamber *f f*, divided into compartments *g g* &c. by partitions *h h*, &c. in close contact with nipple-tubes *i i* &c. upon which the percussion caps are to be placed.

h' h' is a spring-hammer actuated by pulling a rod *i' i'* the forked end *k* of which engages with a projecting lip of the hammer. The rod *i' i'* is retracted so as to be ready for another operation by a spiral 80 spring *l*. Thus it will be seen that the charge will be ignited by simply pulling the rod *i' i'* which operation also causes the cover *b b* of the casing *a a* to fly open, by the motion of the hammer *h h* which as it 85 is drawn back disengages the upper end of a lever *m* from the cover *b b* which is then thrown open by a spring *n*.

The interior apparatus (turning upon a 90 vertical shaft *j*) is made to receive an intermittent rotary motion in such a manner as to bring each nipple-tube in succession in position to be acted upon by the hammer whereby the charges can be ignited one after the other as rapidly as may be desired by 95 the action of a stud *o* on the rod *i' i'*, which plays in the continuous cam-shaped grooves *p p* &c. formed in or on the cylinder *c c*. The grooves are so formed, as shown in Figs. 1 and 2, that by pulling the rod *i' i'* the 100 stud *o* will travel down the grooves until it passes beyond the points *q q* &c. so that when the rod is released and retracted the stud *o* will travel up the next groove until it passes a similar point *r*, when it is ready 105 and in position to travel downward again on pulling the rod *i' i'*, the apparatus being held stationary after each discharge, by the

entering of the stud *o* into the shoulders *s* of the grooves *p p*.

Having thus described my improvements I shall state my claims as follows:

5 What I claim as my invention and desire to have secured to me by Letters Patent is—

1. A portable revolving signal apparatus containing a series of pyrotechnic charges such as blue lights or rockets &c. and oper-

10 ated so as to receive an intermittent rotary motion and to successfully ignite the several

charges by any suitable arrangement of mechanical devices.

2. The arrangement of devices for rotating the apparatus and igniting the charges 15 at the same time, the same consisting of the spring-hammer and cam-grooved cylinder *c* both actuated as described by the rod.

THOMAS T. WOODWARD.
